UNITED STATES PATENT OFFICE.

EVELYN P. SPERRY, OF OAK PARK, ILLINOIS.

MECHANISM FOR OPERATING AND SECURING WINDOWS.

No. 823,195.

Specification of Letters Patent.

Patented June 12, 1906.

Application filed August 12, 1905. Serial No. 273,880.

To all whom it may concern:

Be it known that I, EVELYN P. SPERRY, a citizen of the United States, residing at Oak Park, in the county of Cook and State of Illinois, have invented certain new and useful Improvements in Mechanisms for Operating and Securing Windows, of which the following is a specification.

My invention relates to that class of mechanisms for operating and securing windows having an operating-lever provided with means for securing it to a suitable support, such as a window-frame, means for flexibly securing it to the window to be operated, and means for securing the operating-lever in different adjusted positions.

The principal object of my invention is to provide a simple, economical, and efficient mechanism for operating and securing windows.

Further objects of the invention are to provide means for operating the window from the inside to different adjusted positions and means for rigidly holding the window locked in any desired open position to which it may be adjusted and for holding it locked in closed position, such operating and locking mechanism being adapted to be operated from the inside and inaccessible from the outside.

Other and further objects of the invention will appear from an examination of the drawings and the following description and claims.

The invention consists principally in an apparatus having an operating-lever provided with means for pivotally securing it to a suitable support, such as the window stool or sill, means for flexibly securing such operating-lever to the window to be operated and means for locking the operating-lever, and thereby the window, in different adjusted positions.

It consists, further, in providing such operating and locking lever mechanism with a supplementary connecting device for holding the window securely locked in closed position independently of the operating-lever mechanism and means for securing the operating-lever mechanism operatively to the window in such a manner that the screws or similar elements are inaccessible when the window is open.

It consists, further and finally, in the features, combinations, and details of construction hereinafter described and claimed.

In the accompanying drawings, Figure 1 is a plan view of my improved window operating

and securing mechanism, showing it connected with the window and in locked position, the window being closed; Fig. 2, a plan view showing the window partially open and the operating mechanism in a corresponding position and unlocked; Fig. 3, a view in elevation, showing the operating mechanism in closed position; and Fig. 4, a transverse sectional elevation taken on line 4 of Fig. 1 looking in the direction of the arrow.

In constructing a window provided with my improved operating and locking mechanism I provide a window having a sash *a*, hinged to the window-frame *b* by means of hinges *c*, the window shown in the drawings being a casement-window adapted to be swung in a horizontal plane to open and closed positions. For operating and locking the window from the inside and holding it in different adjusted positions and locked in such manner that the locking mechanism is inaccessible from the outside I provide a main operating-lever *d*, which is secured to the sill *c'* of the window beneath the inside window-sill.

In order to provide suitable means for pivotally securing the operating-lever to the window-sill, the lever is provided with a perforation adapted to receive a pivot-pin *e* in the form of a rivet or screw by means of which such lever is pivotally secured to a metallic base-plate *f*, which base-plate is in turn secured to the window-sill or lower inner portion of the window-frame formed by the window-sill and apron by means of screws *g*. This operating-lever is operatively connected with the window-sash by means of a connecting link or lever *h*, which is pivotally connected with the outer swinging end of the operating-lever by means of a rivet *i*, and a rear end portion *j* of the connecting-lever *h* is pivotally connected with a link *k* by means of a rivet *l*, the link being pivotally connected with the base-plate by means of a rivet *m*. The end of the lever *h* adjacent to the window is flexibly connected with the window-sash by means of sliding operating-rod *n*, which is slidably mounted in a bracket *o*, having perforated lugs *p*, through which such sliding rod extends. This rod is flexibly connected with the adjacent end of the lever *h* by means of a metallic lug portion *q*, which may be integral with the rod, and by a rivet *r*, which forms a pivotal connection between the lever *h* and the sliding rod. The sliding rod or bar *n* is of sufficient length to extend over the screws or bolts *s*, which secure the brackets

to the window-sash. These screws are thus constantly covered by the rod or bar and are inaccessible when the window is open.

The main operating-lever is provided with a serrated or toothed segment *t*, the toothed end of which extends in the arc of a circle and the center of which forms the pivotal center of the operating-lever. A toothed pawl *u* is pivotally mounted adjacent to such toothed segment upon pivot *v*, which is provided with a hook portion *w*, adapted to engage the end of the lever *h* and extends partly around the rivet *r* when the window is closed, thus forming, in connection with the lug *q*, slideable bar *n*, and brackets *o*, a direct connection with the window-sash independently of the operating-lever mechanism.

A locking-lever *y* is pivotally mounted upon the base-plate upon pivot-pin *z* adjacent to the swinging end of the securing-pawl and on the opposite side of such pawl from its toothed edge. The end portion *2* of this locking-lever which is adjacent to the securing-pawl is in sliding engagement with a concaved or curved side *3* of the securing-pawl and is adapted to be moved to the position shown in Fig. 1 to engage such securing-pawl at a point substantially at right angles to a line drawn from the pivot *z* to the pivot *v* of the pawl. When in this position, it will be readily seen that the locking-lever securely holds the pawl locked in engagement with the toothed segment portion of the operating-lever.

To release the operating-lever, and thereby the window, the locking-lever *y* is moved to the position shown in Fig. 2. In moving to this position its inner end engages the lug *4* of the securing-pawl and becomes disengaged from the curved surface portion thereof, so that the pawl is moved out of engagement with the toothed segment and the hook *w* out of engagement with the lever *h* and the window thus released. By this arrangement it will be readily seen that the inside window-stool may be mounted over the window operating and locking mechanism above described and that the window-screen 5 may extend between the locking-lever mechanism and the inner end of the operating-lever and the window. It will also be noted that the connecting-levers *h* and *k* are pivotally connected, respectively, with the window-sash and window-sill, the connection with the window-sill being intermediate the opposite ends of the lever *h* when the window is closed. The main operating-lever is also pivotally connected with the lever *h* in such a manner as to increase the movement of the window with relation to the movement of the main operating-lever as such lever is moved in the direction necessary to open the window. It will also be seen that this manner of connecting the operating-levers and window provides an exceedingly rigid connection between the

window and window-sill when the former is in open position, as shown in Fig. 2.

The main operating-lever is provided at its inner end with an operating-handle 6, which may be of any ordinary and well-known form, and a locking-lever is provided with a handle 7, also of any ordinary and well-known form. I prefer, however, that these handles should extend downward inside of and beneath the window-stool, so as to be inaccessible from without and readily operated from within.

By the above arrangement it will be seen that a window operating and locking mechanism is provided adapted to operate a casement-window and to securely lock it in desired adjusted position, either open or closed, that the means for securing the operating-levers to the window-sash enables the screws to be covered so as to be inaccessible when the window is open, and that the locking and operating mechanism is inaccessible for the purposes of operating the window or locking or unlocking it from without.

I claim—

1. In an apparatus of the class described, the combination of an operating-lever provided with means for pivotally securing it to the window-frame and having a curved toothed edge portion, a securing-pawl movably mounted adjacent to such toothed portion of the main operating-lever, means for operatively securing the main operating-lever to the window, and means for locking and unlocking the securing-pawl and thereby the operating-lever and window.

2. In an apparatus of the class described, the combination of an operating-lever provided with means for pivotally securing it to the window-frame and having outwardly and inwardly swinging end portions, connecting mechanism secured to the window-frame and pivotally connected to the outer swinging end of such operating-lever, and a hook pivotally mounted and movable into and out of engagement with such window-operating mechanism when in closed position.

3. In an apparatus of the class described, the combination of an operating-lever provided with means for pivotally securing it to the window-frame and having outwardly and inwardly swinging end portions, connecting mechanism secured to the window-sash and pivotally connected to the outer swinging end of such operating-lever, a securing-pawl movably mounted adjacent to the main operating-lever and means for locking such securing-pawl in locking engagement with the main operating-lever.

4. In an apparatus of the class described, the combination of a main operating-lever provided with means for pivotally securing it to a suitable support and having a toothed locking-segment portion, means for flexibly securing one end of such lever to the window

to be operated, securing-pawl mechanism movable into and out of engagement with such toothed segment, and means for locking and unlocking such securing-pawl and thereby the main operating-lever and window.

5. In an apparatus of the class described, the combination of a main operating-lever provided with means for pivotally securing it to a suitable support and having a toothed locking-segment portion, means for flexibly securing one end of such lever to the window to be operated, securing-pawl mechanism movable into and out of engagement with such toothed segment and provided with a hook mounted thereon, means for connecting such hook with the window when in closed position, and means for operating such securing-pawl and hook and thereby releasing and locking the window.

10. In an apparatus of the class described, the combination of a main operating-lever provided with means for pivotally securing it to a suitable support and having a toothed locking-segment portion, means for flexibly securing one end of such lever to the window to be operated, securing-pawl mechanism movable into and out of engagement with such toothed segment, and interlocking mechanism for securing the window in closed position independently of the operating-lever.

15. In an apparatus of the class described, the combination of an operating-lever, means for pivotally securing such operating-lever to a window-sash, a connecting-lever pivotally secured to such operating-lever, bracket mechanism, means for securing such bracket mechanism to the window-sash, a rod slidably mounted in such bracket mechanism pivotally connected with the connecting-lever and covering the means for securing such bracket mechanism to the window-sash, and means for locking and unlocking the operating-lever.

20. In an apparatus of the class described, the combination of a pivotal main operating-lever having outer and inner swinging end portions, a base-plate upon which such lever is pivotally mounted, a lever pivotally secured to the outer end of such main operating-

lever and flexibly secured to the window, a link pivotally connected to the end of such connecting-lever opposite that which is connected with the window and pivotally connected with the base-plate, and means for locking and unlocking such main operating-lever and thereby the window.

25. In an apparatus of the class described, the combination of a pivotal main operating-lever having outer and inner swinging end portions and provided with a toothed locking-segment, a base-plate upon which such lever is pivotally mounted, a lever pivotally secured to the outer end of such main operating-lever and flexibly secured to the window, a link pivotally connected to the end of such connecting-lever opposite that which is connected with the window and pivotally connected with the base-plate, a securing-pawl pivotally mounted adjacent to the toothed portion of such locking-segment, and means for locking and unlocking such securing-pawl and toothed segment mechanism and thereby the main operating-lever and window.

30. In an apparatus of the class described, the combination of a pivotal main operating-lever having outer and inner swinging end portions and provided with a toothed locking-segment, a base-plate upon which such lever is pivotally mounted, a lever pivotally secured to the outer end of such main operating-lever and flexibly secured to the window, a link pivotally connected to the end of such connecting-lever opposite that which is connected with the window and pivotally connected with the base-plate, a securing-pawl pivotally mounted adjacent to the toothed portion of such locking-segment, a locking-lever for locking and unlocking said securing-pawl, a bar slidably mounted upon the window-sash and pivotally connected with the lever mechanism, and means for connecting such slideable bar mechanism with the securing-pawl and disengaging it therefrom.

EVELYN P. SPERRY.
